ATTORNEYS

UNITED STATES PATENT OFFICE.

OTTO E. UHLMANN, OF GRAND RAPIDS, MICHIGAN.

DESIGN FOR A SIGNAL LIGHT FOR AUTOMOBILES.

Application filed October 13, 1926. Serial No. 19,322. Term of patent 3½ years.

To all whom it may concern:

Be it known that I, OTTO E. UHLMANN, a citizen of the United States, residing at Grand Rapids, in the county of Kent and State of Michigan, have invented a new, original, and ornamental Design for Signal Light for Automobiles, of which the following is a specification, reference being had to the accompanying drawing, forming part thereof.

Figure 1 is a front elevation of the device, and

Figure 2 is a side elevation of the device shown in Figure 1.

The drawing is lined to denote the colors red and green.

I claim:

The ornamental design for a signal light for automobiles, as shown and described.

OTTO E. UHLMANN.
